UNITED STATES PATENT OFFICE.

SAMUEL BARNES, OF LOVELAND, COLORADO, ASSIGNOR OF ONE-HALF TO
DAVID BARNES, OF SAME PLACE.

GRAIN SEPARATOR AND GRADER.

SPECIFICATION forming part of Letters Patent No. 576,990, dated February 9, 1897.

Application filed May 5, 1896. Serial No. 590,360. (No model.)

To all whom it may concern:

Be it known that I, SAMUEL BARNES, a citizen of the United States of America, residing at Loveland, in the county of Larimer and State of Colorado, have invented certain new and useful Improvements in Grain Separators and Graders; and I do declare the following to be a full, clear, and exact description of the invention, such as will enable others skilled in the art to which it appertains to make and use the same, reference being had to the accompanying drawings, and to the letters and figures of reference marked thereon, which form a part of this specification.

15 My invention relates to improvements in grain-separators specially adapted for separating oats (both common and wild) from wheat and other grains; and to this end the invention consists of the features, arrangements, and combinations hereinafter described and claimed, all of which will be fully understood by reference to the accompanying drawings, in which is illustrated an embodiment thereof.

25 In the drawings, Figure 1 is a side elevation of the machine. Fig. 2 is a top or plan view of the same. Fig. 3 is a fragmentary top view with the table removed to show the mechanism underneath. Fig. 4 is a similar view with the table in place. Fig. 5 is a section taken on the line *x x*, Fig. 4. Fig. 6 is a section taken on the line *y y*, Fig. 4. Fig. 7 is a detail of construction, the parts being shown on a larger scale. Fig. 8 is a section taken 35 through the worm-shaft on the line *z z*, Fig. 3. Fig. 9 is a section taken through the lower edge of the apron to illustrate the flap protecting the lower propelling-chain.

Similar reference-characters indicating corresponding parts in the views, let the numeral 5 designate a suitable frame upon which is mounted an inclined table 6, surrounded by an endless apron 7, propelled by drums 8, journaled in the frame. This apron consists 40 of a blanket composed of fibrous fabric or any other suitable material to which the oats will adhere. The apron has a movement in a direction at right angles to the inclination of the table. The table's inclination is preferably at an angle of about forty-five degrees.

Attached to the frame and projecting a short distance above the apron are two parallel bars 9, suitably separated. To the bars 9 are attached slats 12. The extremities of the slats are made fast to the bars. To the 55 slats are attached flaps 10, composed of some suitable flexible material. The lower extremities of the flaps engage the top of the apron. The flaps and their supporting-slats preferably occupy a diagonal position with 60 reference to the apron's movement. The movement of the apron is in the direction indicated by the arrows. (See Fig. 1.)

The grain to be treated is fed upon the upper left-hand corner of the apron farther to 65 the right, (referring to Fig. 1.) As the apron moves forward, or in the direction indicated by the arrows, the wheat, which is heavier, rolls downward in a direction transverse to the apron's movement, passes under the flaps 70 10, and finally falls from the lower edge of the apron into a suitable receptacle 30. The oats naturally cling to the apron, but if it were not for the flaps the wheat would carry some oats downward with it and prevent the 75 obtaining of the most satisfactory results. Hence while the flaps allow the wheat to pass under them they cause the oats to cling more tenaciously to the apron, and thus prevent any oats from escaping with the wheat which 80 falls from that part of the apron engaged by the flaps. These flaps engage the greater portion of the apron's upper surface. Let A designate said portion, and B the portion of the apron forward or beyond the flaps. The 85 wheat which falls from the part A of the apron is free from oats. Some wheat, however, passes to the part B of the apron and would be carried over with the tailings were it not for the agitating devices placed on top of the 90 table and located between the flap-supporting frame and the forward end drum. These devices consist of two slats 13 and 14, located beneath the apron and occupying a position transverse to the apron's movement. The 95 upper extremities of these slats are fastened to the table or to the framework, while their lower extremities are free and project slightly beyond the lower edge of the table.

Beneath the table and fulcrumed on the 100

frame at 15 is a lever 16, whose upper extremity is engaged by a double cam 17. To the lower extremity of this lever is attached an upwardly-projecting pin 18, adapted to 5 engage the lower extremity of the agitator 13. The pin 18 passes through a stop 19. Between this stop and the end of the lever is located a coil-spring 20. As the cam 17 depresses the upper extremity of the lever 16 10 the lower end of said lever is raised, thus bringing the upper end of the pin 18 in contact with the agitator 13. This movement of the lever compresses the spring, and as soon as the cam releases the upper end of the lever 15 the recoil of the spring returns the lever to its normal position. The slat 14 is actuated through the intervention of a short lever 21, fulcrumed at 22. One end this lever 21 occupies a position below and in contact with 20 the lower extremity of the lever 16, while its opposite extremity engages the lower extremity of the agitating-slat 14. As the lower extremity of the lever 16 moves downward under the influence of the spring, as heretofore explained, it throws the opposite extremity of the lever 21 upward and moves the agitating-slat 14 accordingly. Thus the two slats 13 and 14 are alternately raised and lowered underneath and in contact with the 25 moving apron. In this manner the part B of the apron is kept in such a state of vibration that the wheat which has been carried forward beyond the flaps 12 is made to roll downward into an auxiliary receptacle 23. This vibration, caused by the agitating devices, 30 causes some oats also to leave the apron with the wheat. Hence the contents of the auxiliary receptacle are returned via a carrier 24 and discharged into the supply-bin 25 for treatment. The grain to be cleaned or separated from the oats is originally discharged 35 into the bin 25 and carried thence via an elevator 26 and discharged into the hopper 27 via a chute 28. From thence it is fed to the apron through the instrumentality of a suitable feed-roll 29.

The portion of the machine nearest the top of the sheet in Fig. 2 may be designated the rear. Bearing this in mind the grain, when 40 it leaves the hopper, is discharged upon that portion of the apron passing over the upper left-hand corner of the table farther to the rear.

The power for propelling the machine may 45 be obtained from any suitable motor. As shown in the drawings, a belt 31 leads from the motor to a pulley 32 on a shaft 33. A sprocket-wheel on the shaft 33 is connected by means of a chain 34 with another sprocket 50 on a shaft 35. This last-named shaft carries a worm 36, engaging a gear 37, fast on the upper journal of the forward drum 8. The drums 8 carry sprockets 39, which are engaged by the chains 38, attached to the edges 55 of the apron. The lower chain is concealed by a flap 7^a, attached to the apron to prevent the chain from interfering with the grain as

it falls into the receptacles 30 and 23. Hence the apron is slowly propelled through the instrumentality of the worm-gear. A crossed 70 belt 40 connects a pulley on the shaft 33 with another pulley on a shaft 41. This last-named shaft carries a gear 42, meshing with another gear 43 on the journal of the feed-roller 29. A belt 44 connects a pulley on the 75 shaft 33 with another pulley on the upper journal of the elevator 26. The carrier 24 is propelled by means of a belt 45, leading from a pulley on the shaft 33 to a pulley 46 on one journal of the elevator. 80

Underneath the endless apron is a reel 47, suitably journaled in the stationary frame. The slats 47^a of this reel engage the apron underneath and remove all the oats which 85 adhere thereto. There is a bevel-gear connection 49 between the shaft 33 and the shaft 47^c of the reel for operating the latter.

My improved machine is a grader as well as a separator, since all the cracked kernels, as well as those that are shrunken and worthless for any reason, are carried over by the apron and discharged with the tailings, since they are not of sufficient specific gravity to cause them to roll down under the flaps 10 into the receptacle 30. 90

Having thus described my invention, what I claim is—

1. In a grain-separator, the combination with a suitable frame, of an inclined table mounted thereon, the drums journaled in the 100 frame at the ends of the table, an endless apron surrounding the table and engaging the drums, said apron having a movement transverse to the inclination of the table, flaps supported above and engaging the apron 105 and occupying a diagonal position with reference to its direction of movement, an agitating device supported on the table underneath the apron, said device being located between the flaps and the forward-end drum, 110 means for feeding the grain to the apron, and means for propelling the latter, substantially as described.

2. In a grain-separator, the combination with a suitable frame, of an inclined table 115 mounted thereon, an endless apron surrounding the table, means for propelling the apron in a direction at right angles to the inclination of the table, the flaps suitably supported above and engaging the apron, an agitating 120 device supported on the table underneath the apron, said device being located between the flaps and the forward end drum, the reel underneath the apron, and suitable means for feeding the grain to the apron, substantially 125 as described.

3. In a grain-separator, the combination with a suitable frame, of the inclined table supported thereon, an endless apron surrounding the table, means for propelling the apron 130 in a direction at right angles to the inclination of the table, the flaps supported above and engaging the apron, and an agitating device supported on the table underneath the

apron, said device being located between the flaps and the forward end drum, substantially as described.

4. In a grain-separator, the combination 5 with a suitable frame, of the inclined table mounted thereon, the endless apron surrounding the table, means for propelling the apron in a direction at right angles to the inclination of the table, an agitating device supported on top of the table and underneath the apron, the upper extremity of said device being made fast while its lower extremity is loose, and means for actuating said device, comprising a lever fulcrumed on the frame,

a spring normally holding the lower extremity of the lever in its lowest position of movement, a projection attached to the lower extremity of the lever and adapted to engage the lower extremity of the agitating device, and suitable means, as a rotating cam, for 20 engaging the upper extremity of the lever, substantially as described. 15

In testimony whereof I affix my signature in the presence of two witnesses.

SAMUEL BARNES.
